CLAIM

(58) **Field of Classification Search**

The ornamental design for a display screen with graphical user interface, as shown and described.

DESCRIPTION

USPC D14/485-495; 345/1.1, 1.2, 2.1-2.3, 3.1,
345/902; 715/763, 810, 836, 837, 846,
715/847, 977

FIG. 1 is a front view of a display screen with graphical user interface, showing the new design; and,
FIG. 2 is a front view of a second embodiment thereof.
The outermost broken lines illustrate a mobile device, which is the environment of the design, and forms no part of the
